UNITED STATES PATENT OFFICE.

HENRY ISBERG, OF PORTLAND, OREGON.

GAME APPARATUS.

1,310,415.

Specification of Letters Patent. Patented July 22, 1919.

Application filed July 6, 1918. Serial No. 243,544.

To all whom it may concern:

Be it known that I, HENRY ISBERG, (who has declared his intention to become a citizen of the United States of America and 5 is a citizen of Sweden,) residing at Portland, in the county of Multnomah and State of Oregon, have invented new and useful Improvements in Game Apparatus, of which the following is a specification.

10 This invention is an improved game apparatus embodying a target having movable numbered figures and also embodying a cross bow and darts to be used for shooting at the figures in the target.

15 With the above and other objects in view, the invention consists in the construction, combination and arrangement of devices hereinafter described and claimed.

In the accompanying drawings:—

20 Fig. 1 is a perspective view of the target. Fig. 2 is a side elevation of the same.

Fig. 3 is a transverse sectional view of the same, folded.

25 Fig. 4 is a perspective view of the cross bow.

Fig. 5 is a similar view of one of the darts.

My improved target is an oblong rectangular board 1 which may be made of wood or other material and which is provided 30 with a cover 2 on its face and is provided with a series of openings 3 which are differently numbered, to indicate points in the game, and are here shown as numbered 1, 2, 3, 4, 5 and 6 respectively. Any suitable 35 number of the openings may be provided.

The cover or face of the target is also provided with figures 4 which are here shown as figures of animals and the head of each animal figure forms a movable target member 40 5 the said target members being here shown as circular and adapted to fit in and close the openings. Each target member is hinged at the lower side and on the rear side of the target board as at 6 and is adapted to 45 fall downwardly and rearwardly and out of its opening when the said target member is struck by one of the darts.

On its rear side the target board is provided with a supporting leg 7 which is

hinged thereto at the center as at 8 and 50 which is adapted to fold against the target board. The leg is provided in its hinged edge with a recess 9 and with a stop shoulder 10. A locking member 11 is hinged to the rear side of the target board as at 12 55 for angular movement in a vertical plane and has a slot 13 in its free side. When the supporting leg of the target is arranged at right angles thereto and in position to support the target in an inclined position the 60 locking member can then be turned to a horizontal position into the recess in the leg and so that the slot of the locking member receives the leg thus holding the leg securely. The locking member by bearing on the stop 65 with which the leg is provided is held in horizontal locking position.

The cross bow which is shown at 15 in Fig. 4 is adapted for shooting the darts 16 one of which is shown in Fig. 5. Each dart 70 has a spherical or substantially spherical head 17, a shank 16 and a widened guiding web 19 at the rear end of the shank and in practice each dart is made from a single piece of suitable wood or other material. 75 The webs of the darts serve to direct them straight in their flight when shot from the cross bow and the blunt heads of the darts prevent them from doing any damage should they miss the target.

80 In playing the game in accordance with my invention each player uses a number of darts corresponding with the number of the movable target members. All the target members are at first in closed position in 85 the openings and it is the object of each player to strike as many of the target members with the darts as he shoots them as his skill admits. When a target member is struck by one of the darts it falls to open 90 position and the number of said target member counts for a corresponding number of points in the game. The player who gets the highest number of points wins the game.

95 While I have herein shown and described a preferred embodiment of my invention, I would have it understood that changes may be made in the form, proportion and con-

struction of the several parts, without departing for the spirit of my invention and within the scope of the appended claim.

Having thus described my invention, I
5 claim:—

In game apparatus of the class described, a target board having movable target members, each movable target member having a

point number, the said target board also having figures and said movable target members forming the heads of said figures and said board having openings adapted to be filled by said target members when the latter are in normal position.

In testimony whereof I affix my signature. 15
HENRY ISBERG.

Copies of this patent may be obtained for five cents each, by addressing the "Commissioner of Patents, Washington, D. C."
